PROCESS AND APPARATUS FOR
RECORDING SOUND

René Léon Adolphe Nublat, Paris, France

Application September 27, 1932, Serial No. 635,032
In France May 19, 1932

2 Claims. Cl. 274—11)

The present invention has for its object a process permitting to obtain, by mechanical means, the recording, and the reproduction of vibrations of any kind especially sounds.

5 The process consists essentially in cutting, by means of a knife or a needle, or any other suitable cutting instrument, actuated by a vibratory apparatus of any type, (operated by the apparatus producing the vibrations to be recorded) a film which consists of an opaque or transparent band, preferably very thin, or any other suitable transparent backing.

10 This cutting is effected at the mean central line of the film, which is thus divided into two parts, wherein the inner edge is formed by the groove traced by the knife of the vibrator and corresponding to the recorded oscillations. The reproduction is effected in a very simple manner, by projecting upon one of the parts of the film 20 thus cut, and spraying thereon a liquid of dark colour, based on acetone or alcohol, and to cause the part thus obtained to travel between a source of luminous radiations, and a photo-electric cell.

15 The process, which forms the object of the present invention can also be used in first blackening the entire film upon its whole surface by means of any liquid, and then cutting the film thus blackened by means of the knife of the vibrator as above stated; it will then suffice to pass 20 one of the halves of the film thus cut between the source of light and the photo-electric cell, thus obtaining simultaneously the recording and the reproduction of vibrations of sounds which is chiefly advantageous in case of test.

25 The invention has further for its object a device for the embodiment of the aforesaid process. This device consists essentially of the combination of a vibratory apparatus operated by the transmitted oscillations and provided with a 30 pointed knife or any other suitable cutting instrument whose point is preferably bevelled, which cuts the film according to the sinuous line corresponding to the vibrations to be recorded, of a support adjustable in height upon which the film 35 travels below the point, of the vibrator knife; of a suitable means for applying, during the reproduction one of the parts of the film cut out during the recording, upon the film to be blackened; of suitable means for then separating after the 40 blackening, the part of the film in question from the blackened film the apparatus being completed, for the reproduction, by a device which projects a sprayed liquid upon a film to be blackened; by a source of luminous radiation and a photo-electric cell of a known type.

In the drawings:

Fig. 1 is an elevational view of the device.

Fig. 2 is an end view of the same.

Fig. 3 is a view in section along A—A of Fig. 1.

Fig. 4 is a view in section along B—B of Fig. 2.

Fig. 5 shows a length of film cut during the recording.

Fig. 6 shows a length of film cut and then blackened for the reproduction.

Figs. 7, 8 and 9 are detail views on a larger scale.

As represented in the drawings, the device permitting to record and to reproduce the sounds on a film 1, in conformity with the invention, comprises a vibratory apparatus 2, of a known type, 15 with electro-magnet, actuated during the recording, by the vibrations which are produced, by the sounds delivered into a microphone of any type, these vibrations being amplified, in the known manner, so as to operate the vibratory apparatus 20

25 This apparatus actuates a knife 3 whose point consists of a diamond point preferably bevelled as shown at 3a (Fig. 8) which cuts the film following its central line, as soon as the vibratory system is put in action. The form of the point of the knife 3 may also vary according to the nature of the vibrations to be recorded. The film 1 consists preferably of a very thin transparent band or other suitable transparent backing.

30 This film is unwound from a reel 4, and travels upon a support 5 which is adjustable in height by means of screws 6.

35 7 is the frame of the machine, 8 are the feeding devices which eventually permit the opaque liquid (hereinafter described) to dry, during the reproduction, before it is wound; the drying is facilitated by a grid 9 which conceals the interior of the frame.

40 During the recording, under the effect of sound vibrations, the point of the knife 3, whose pressure on the film 1 is regulated at 1a to the desired value by the screw 6 traces upon the band the groove or furrow 1c (Fig. 5) corresponding to the recorded vibrations.

45 The film is thus cut at its central line, into two parts 1a and 1b which can very readily be separated from one another, the cut part thus obtained is extremely sharp. The film must be very thin, for it is not possible to record elevated harmonies or high tones on a thick film, because 50 of too slight amplitudes; in the latter case, the slight amplitudes being absorbed by the thickness of the film.

55 By the use of a sprayer or other analogous device 10 operated by compressed air, one projects

upon the film a sprayed liquid, based upon acetone or alcohol, the compressed air enters at 11, and this compressed air is supplied from a recipient 11a by a pipe 11b (Fig. 9) and acts upon the sprayed liquid at 10a, in such manner that this liquid is projected at 10b upon the film to be blackened.

Only the part of the film adjacent to and not covered by the film part which is cut during the recording will be blackened at 1'a (Fig. 6); the part 1'b of this film remains unblackened. The region thus blackened is exactly marked out by the groove corresponding to the recorded vibrations.

The band thus blackened upon one of its halves is automatically separated, by any means, from the part of the film 1a or 1b which partly covers it, and then travels over a photo-electric cell 12, of any type, and near a source of luminous radiations 13, the beam of light passing in the known manner through the aperture 14 provided in the support upon which the film travels before the cell 12.

For copies of the original, one may use, instead of the spraying process as above described, any known photographic process and chiefly in the case of the simultaneous photography of the sound and the image.

15 is an electric motor actuating the mechanism for unwinding the film.

The whole of the above mentioned device may also be used for cutting, by means of a knife 3, a film preliminarily blackened by means of the spraying apparatus 10—11. The film, immediately after it has been blackened, is cut into two parts which are separated from one another by any mechanical means, before the displacement in front of the photo-electric cell.

What I claim as new and desire to secure by Letters Patent of the United States is:

1. The method for recording sound vibrations upon a film tape of transparent material consisting in moving the tape longitudinally over a support and under a vibratory cutter, simultaneously vibrating the cutter by the impact of sound waves whereby an incision is made in the film by the cutter and in applying darkening material to the areas of the tape at the opposite edges of the incision to cloud the transparency of the film.

2. Apparatus for recording sound vibrations comprising a support, a film adapted to move over the support, means for moving the film, a cutter resting upon the film above said support, means for vibrating the cutter as the cutter makes an incision in the film and means adjacent the cutter for spraying darkened material upon the whole surface of the film along the incision.
